United States Patent Office

Des. 186,048
Patented Sept. 1, 1959

186,048

END LINK FOR A BRACELET OR SIMILAR ARTICLE

Sol P. Kaufman, Providence, R.I., assignor to Speidel Corporation, Providence, R.I., a corporation of Rhode Island

Application March 31, 1959, Serial No. 55,262

Term of patent 14 years

(Cl. D45—4)

FIG. 1

FIG. 2

FIG. 3

FIG. 4

FIG. 5

Fig. 1 is a top plan view of an end link for a bracelet or similar article showing my new design;

Fig. 2 is a side elevational view;

Fig. 3 is an end elevational view looking from the right of Fig. 1;

Fig. 4 is an end elevational view looking from the left of Fig. 1; and

Fig. 5 is an enlarged perspective view thereof.

I claim:

The ornamental design for an end link for a bracelet or similar article, substantially as shown.
